UNITED STATES PATENT OFFICE.

RUDOLPH W. GLASNER AND JOHN NELSON, OF CHICAGO, ILLINOIS, ASSIGNEES TO
MARQUETTE TOOL & MANUFACTURING CO., OF CHICAGO, ILLINOIS, A CORPORA-
TION OF ILLINOIS.

BLANK-HOLDING MEANS.

Application filed August 6, 1924. Serial No. 730,352.

This invention relates to improvements in blank holding means and one of the objects of the same is to provide power presses intended for use in connection with sheet metal drawing dies, with means to provide the gripping means of these drawing dies with a substantially unvarying pressure during the stroke of the press, and further to eliminate in the press the objectionable "back lash" 5 caused by the release of this pressure at the bottom of the stroke of the press when the ram of the press is moving upward. This "back lash" takes place at the time when the crank of the press is passing over the center 10 point at the bottom of its stroke or circular movement.

Another object of the invention is to provide presses and dies of this character with even pressure blank gripping means, which 20 will be of a simple construction and of such design as will fit into the ordinary press and die such as are now being used, without necessitating a specially designed press or specially designed dies.

Another object of this invention is to provide presses of larger dimensions with a device of this character built as a unit but covering a larger area of space through an opening in the bed of the press.

Another object of the invention is to provide means for metal drawing dies of the character described which will provide a constant pressure during the up and down movement of the press and still permit a 35 varying pressure at different points throughout the area of the blank gripping means.

To the attainment of these ends and the accomplishment of other new and useful objects as will appear, the invention consists in 40 the features of novelty in substantially the construction, combination and arrangement of the several parts hereinafter more fully described and claimed and shown in the accompanying drawings illustrating this invention and in which,

Figure 1 is a view partly in elevation and partly in section of a draw press having a blank holding means constructed in accordance with the principles of the invention applied thereto and with parts of the press omitted.

Figure 2 is a view of a larger form of press, partly in elevation, partly in section

and with parts omitted and showing applied thereto a plurality of cushioning means for 55 the blank holding means.

Figure 3 is an enlarged detail sectional view of the fluid pressure controlling valves. Referring more particularly to the drawings the numeral 10 designates a portion of a press having a ram 11 which is reciprocable in the ordinary and well known manner. Supported by the press is a bolster plate 12 and mounted upon the bolster plate in any suitable manner is a center or punch block 65 13, with which a female die member 14 cooperates to shape the article, the die member 14 being connected with the ram 11 for movement therewith. Cooperating with the center block or punch 13 is a draw ring 15 which latter is supported by means of suitable die pins 16 that pass loosely through the bolster plate 12 and rest upon a suitable pressure pad or member 17 below the bolster plate. Connected with the bolster plate 12 and depending therefrom is a stationary bar or rod 18, one end of which is secured to the bolster plate preferably by being screwed thereinto. This rod 18 passes loosely through the pressure pad 17 and extends for any desired distance below the bolster plate 12. The lower extremity of the rod 18 is threaded as at 19 to receive a nut or collar 20 and upon which nut or collar a spring supporting plate 21 rests, and the rod 18 loosely 80 passes through the plate 21. Encompassing the rod 18 and resting upon the plate 21 by one end is a coil spring 22 upon the upper end of which spring rests another spring plate 23 that loosely surrounds the stationary rod 18. Loosely surrounding rod 18, above the plate 23 and resting thereupon by one end thereof, is a sleeve 24 which is provided with external screw threads to receive a nut or collar 25. Resting upon the nut or collar 25 and loosely encompassing the rod 18 and sleeve 24 is a spring supporting plate 26 which latter is spaced for a considerable 90 distance below the pressure pad 17. A coil spring 27 loosely encompasses the rod 18, and one end of this spring engages the plate 26 while the other end of the spring engages the pressure pad 17.

Pins or rods 28 engage the spring plate 23 by one end and rest thereupon. The other 105 ends of these pins or rods 28 have engage-

ment with the ram 11, so that when the ram is moved downwardly the rods 28, which pass loosely through the bolster plate and also preferably through the spring plates 17 and 26, will cause the spring 22 to be compressed. As the ram ascends the spring 22 causes the pins 28 to follow the ram.

Upon the downward movement of the ram 11 the draw ring 15 will be depressed by the female die member 14, and the draw ring will, through the medium of the pins 16, which latter pass loosely through the bolster plate 12 and engage the spring plate 17, depress the latter against the stress of the spring 27.

The spring 27 operates to control the draw ring 15 and the tension of the spring 27 may be varied by adjusting the nut or collar 25 upon the sleeve 24. The action of the pins 28 upon the spring 22 through the medium of the plate 23 will compress the spring, while the action of the pins 16 upon the plate 17 will compress the spring 27. This combined action tends to impart a substantially unvarying pressure to the draw ring 15 and to relieve the ram of the press from considerable resistance of the draw ring.

Connected with the spring plate 23 for movement therewith is a cylinder 29 within which is arranged a piston 30. The piston is preferably connected with the rod 18 so as to be maintained stationary while the cylinder 29 is reciprocable with respect to the piston. If desired the rod 18 may be of a sectional construction, the piston being connected with one section and the other section being secured to and depending from the cylinder to support the plate 21 and spring 22.

40 The cylinder 29 is supplied on the lower side of the piston 30, with a suitable fluid from a suitable source of supply, such as a pressure tank not shown which latter has communication with the cylinder 29, through the medium of a pipe 32, and the pipe may, if desired, pass loosely through an opening 33 in the member 21. Arranged in the connection 32 between the cylinder 29 and source of fluid supply, is a valve casing 34 which is provided with a passage 35 that connects with the pipe 32, and this passage is controlled by a spring controlled valve 36 having means 37, for varying the stress of the valve 36. The valve 36 is so arranged that it will be unseated by the fluid flowing through the pipe 32 under pressure from the source of supply to the cylinder but when it is attempted to force the fluid back into the source of supply, the valve 36 will close the passage. A by-pass 38 is connected with the pipe 32 in advance of the valve 36 and is also connected with the valve casing 34, behind the valve, a spring controlled valve 39 being also provided in the casing to control the by-pass passage. An adjusting

device 40 may be provided for varying the stress of the valve 39.

The pipe 32 may be provided with a flexible section 41 so as to permit the cylinder 29 to be bodily moved with respect to the piston 30. The valve 39 is arranged in opposition to the valve 36 so that when pressure is exerted upon the fluid to cause it to flow from the tank 31 into the cylinder 29 on the bottom side of the piston 30, the valve 36 will open to permit such passages of the fluid and the valve 39 will close. When, however, the piston 30 and cylinder 29 are relatively moved in the opposite direction the fluid will be forced from the cylinder 29 back into the tank. At this time the valve 36 will close and the valve 39 will open to permit the fluid to flow through the passage 41 in the valve casing 34 back into the tank 31 through the pipe 32.

Obviously the elements 37 and 40 may be adjusted to vary the pressure necessary to unseat the respective valves 36, 39.

In operation and assuming the ram 11 to be elevated, the pressure pad 17 will rest against the bottom of the bolster plate 12 and the top of the draw ring 15 will be substantially flush with the center punch or die 13. The spring plate 23 will also be elevated to the limit of its upward movement and will be maintained in such elevated position through the stress of the spring 22; the sleeve 24 serving to prevent a further rising movement of the plate 23.

With the parts in this position the blank to be formed is laid on top of the draw ring 15 and across the center punch or die 13. As the press ram 11 descends, carrying with it the female die member 14, the lower face of this die 14 will engage the blank and hold it between the die 14 and upper surface of the draw ring 15. The pins 16 engaging the pressure pad 17, will move the pad against the pressure of the top spring and the stress of the spring 27, will be exerted upon the blank to be drawn, thereby holding the blank at the correct tension to prevent wrinkling of the metal.

During the descending movement of the ram 11 the pins 28 are in contact with the press ram at the same time that the die engages the blank. The ram then pushes against the lower spring 22 through the plate 23, and in this manner relieves the draw ring of the increasing pressure which would otherwise be caused through the compression of the top spring 27 and takes this increasing pressure off the blank to be drawn, so that the blank is thereafter held at the initial pressure during the entire downward movement of the press.

During this operation the fluid on the top side of the piston 30 will escape through the opening 18^a in the rod 18 and fluid on the bottom side of the piston 30 will flow

through the control valve 39 and this valve may be so set that it will retard the upward movement of the cylinder 29. The action of the fluid in this cylinder and through the medium of the various connections and parts will retard the upward movement of the pressure pad 17 which supports the die pins 16 and draw ring 15.

This will eliminate the so called "back lash" of the press and will relieve the press clutch of great strain, and also prevent the so called "repeats" which are caused by the momentum of the ordinary cushioning device, and also will eliminate accidents.

There is shown in Figure 2 of the drawing a press having an extended or much greater capacity than the press shown in Figure 1, and has connected with a plurality of the cushioning devices shown in Figure 1. In this form of the invention a supporting plate 42 is provided for supporting the cushioning devices and is suspended beneath the press in any desired or suitable manner, such as by means of hanger rods 43 each one of which passes through a suitable eye or projection 44, on the body of the press 45. These rods 43 pass loosely through the plate 42 and have connected with their free extremity a nut or collar 46 which is threaded thereupon. A sleeve 47 encompasses the lower end of the bar or rod 18 and also loosely passes through the plate 42, so that the plate 21 of the respective cushioning devices which is engaged by one end of the lower spring 22, may be readily adjusted with respect to the support 42, by adjusting the respective nut or collar 20.

With this form of the invention the pins 16 of the cushioning means pass loosely through the bolster plate 12 and all engage a common plate 48 against which the upper ends of the springs 27 of the cushioning means engage and which plate 48 serves the same function as the pressure pad 17.

It will be manifest that with this form of the invention there will be a substantially constant pressure upon the draw ring 15 by all of the cushioning devices during the operation of the press, but inasmuch as each of the cushioning devices is provided with an independent means for varying at will the stress of the springs of the respective cushioning devices, they may be independently adjusted with respect to each other as to produce or permit different pressures of the draw ring at various points throughout the area of the draw ring.

At the same time the piston and cylinder attachment provides a means by which the "back lash" will be prevented or overcome, and which "back lash" in presses of this character occurs at the time when the press crank is passing the bottom of its stroke and just as the ram begins to recede and

at the time when the stress of the ram is relieved from the draw ring.

While the preferred forms of the invention have been herein shown and described, it is to be understood that various changes may be made in the details of construction and in the combination and arrangement of the several parts, within the scope of the claims, without departing from the spirit of this invention.

What is claimed as new is:—

1. A draw press including a forming die, a movable element co-operating with the die, a blank holding member, resiliently yielding means for resisting the movement of the blank holding member, a second resiliently yielding means also operable to resist the movement of the blank holding member, means responsive to the movement of the said movable element and operating to relieve the pressure of the second recited yielding means upon the said blank holding member, and fluid pressure means operating to retard the return movement of the said blank holding means when the said movable member recedes.

2. A draw press including a forming die, a movable element co-operating with the die, a blank holding member, resiliently yielding means for resisting the movement of the blank holding means, a second resiliently yielding means also operable to resist the movement of the blank holding member, means responsive to the movement of the said movable element and operating to relieve the pressure of the second recited yielding means upon the said blank holding member, and fluid pressure means operating to retard the return movement of the said blank holding means when the said movable member recedes, the said fluid pressure means embodying a relatively movable cylinder and piston one operatively connected with the blank holding member and the other anchored to a stationary part of the press and means for supplying fluid to the cylinder.

3. A draw press including a forming die, a movable element co-operating with the die, a blank holding member, a plurality of separate and resiliently yielding means operating upon the blank holding member, means whereby the said movable element will at a predetermined point in the cycle of operation of the press directly operate upon one of the said resiliently yielding means to prevent an increasing pressure of the other of the resiliently yielding means upon the said blank holding member, whereby the work will be held by the blank holding member at a substantially unvarying pressure during the stroke of the press, and additional means for restraining the return movement of the blank holding means.

4. A draw press including a forming die, a movable element co-operating with the

- 1 die, a blank holding member, a plurality of separate and resiliently yielding means operating upon the blank holding member, means whereby the said movable element will at a predetermined point in the cycle of operation of the press directly operate upon one of the said resiliently yielding means to prevent an increasing pressure of the other of the resiliently yielding means upon the said blank holding member, whereby the work will be held by the blank holding member at a substantially unvarying pressure during the stroke of the press, and fluid pressure means for restraining the return movement of the blank holding means, said fluid pressure means including a relatively movable cylinder and piston one of which is operatively connected with the blank holding means and the other anchored to a stationary part of the press and means for supplying fluid to the cylinder.
- 5 2. A draw press including a forming die, a movable member co-operating with the die, a blank holding member, superposed and separate resiliently yielding elements resisting the movement of the blank holding member, means whereby a movable part of the press will operate directly upon one of the said elements to relieve the pressure of the other of the resiliently yielding means upon the blank holding member, and fluid pressure means operating to retard the return movement of the said blank holding means when the said movable member recedes.
- 10 3. A draw press including a forming die, a movable member co-operating with the die, a blank holding member, superposed and separate resiliently yielding elements resisting the movement of the blank holding member, means whereby a movable part of the press will operate directly upon one of the said elements to relieve the pressure of the other of the resiliently yielding means upon the blank holding member, and fluid pressure means operating to retard the return movement of the said blank holding means when the said movable member recedes.
- 15 4. A draw press including a forming die, a movable member co-operating with the die, a blank holding member, superposed and separate resiliently yielding elements resisting the movement of the blank holding member, means whereby a movable part of the press will operate directly upon one of the said elements to relieve the pressure of the other of the resiliently yielding means upon the blank holding member, and fluid pressure means operating to retard the return movement of the said blank holding means when the said movable member recedes.
- 20 5. A draw press including a forming die, a movable member co-operating with the die, a blank holding member, superposed and separate resiliently yielding elements resisting the movement of the blank holding member, means whereby a movable part of the press will operate directly upon one of the said elements to relieve the pressure of the other of the resiliently yielding means upon the blank holding member, and fluid pressure means operating to retard the return movement of the said blank holding means when the said movable member recedes.
- 25 6. A draw press including a forming die, a movable member co-operating with the die, a blank holding member, superposed and separate resiliently yielding elements resisting the movement of the blank holding member, means whereby a movable part of the press will operate directly upon one of the said elements to relieve the pressure of the other of the resiliently yielding means upon the blank holding member, and fluid pressure means operating to retard the return movement of the said blank holding means when the said movable member recedes, and means individual to the said elements for varying at will the stress of said elements.
- 30 7. A draw press including a forming die, a movable member co-operating with the die, a blank holding member, superposed and separate resiliently yielding elements resisting the movement of the blank holding member, means whereby a movable part of the press will operate directly upon one of the said elements to relieve the pressure of the other of the resiliently yielding means upon the blank holding member, and fluid pressure means operating to retard the return movement of the said blank holding means when the said movable member recedes, the said fluid pressure means embodying a cylinder and piston relatively movable, one of the
- 35 parts being connected with the blank holding member and the other being anchored to a stationary part of the press, and means for supplying fluid to the cylinder.
8. A draw press including a forming die, a movable member co-operating with the die, a blank holding member, superposed and separate resiliently yielding elements resisting the movement of the blank holding member, means whereby a movable part of the press will operate directly upon one of the said elements to relieve the pressure of the other of the resiliently yielding means upon the blank holding member, and fluid pressure means operating to retard the return movement of the said blank holding means when the said movable member recedes, the said fluid pressure means being encompassed by the said resiliently yielding means.
9. A draw press including a forming die, a movable element co-operating with the die, yielding blank holding means, and spring cushioning means providing the said blank holding means with a substantially unvarying pressure during the operative stroke of the said movable element, the last recited means including a plurality of resilient elements independent of each other and means individual to the said movable element and the said blank holding means for respectively controlling the operation of the said resilient elements, one of the said means which is individual to the movable element and the blank holding means operating at a predetermined time in the cycle of operation of the press to relieve the blank holding means of the stress of its respective resilient element.
10. A draw press including a forming die, a movable element co-operating with the die, yielding blank holding means, spring cushioning means providing the said blank holding means with a substantially unvarying pressure during the operative stroke of the said movable element, the last recited means including a plurality of resilient elements and means individual to the said movable element and the said blank holding means for respectively controlling the operation of the said resilient elements, and means for varying at will the stress of the said spring cushioning means.
11. A draw press including a forming die, a movable element co-operating with the die, yielding blank holding means, spring cushioning means providing the said blank holding means with a substantially unvarying pressure during the operative stroke of the said movable element, the last recited means including a plurality of resilient elements and means individual to the said movable element and the said blank holding means for respectively controlling the operation of one of the said resilient elements, and means individual to the said resilient

elements for varying at will the stress of the last recited elements one independently of the other.

12. A draw press including a forming die, 5 a movable element co-operating with the die, yielding blank holding means, spring cushioning means providing the said blank holding means with a substantially unvarying pressure during the operative stroke of the 10 said movable element, the last recited means including a plurality of resilient elements and means individual to the said movable element and the said blank holding means for respectively controlling the operation of 15 one of the said resilient elements, and means for restraining "back lash" caused by the release of the pressure upon the blank holding means as the said movable element recedes.
13. A draw press including a forming die, 20 a movable element co-operating with the die, yielding blank holding means, spring cushioning means providing the said blank holding means with a substantial unvarying pressure during the operative stroke of the 25 said movable element, the last recited means including a plurality of resilient elements and means individual to the said movable element and the said blank holding means for respectively controlling the operation of 30 the said resilient elements, and fluid pressure means for restraining "back lash" caused by the release of the pressure upon the blank holding means as the said movable 35 element recedes.

14. A draw press including a forming die, 40 a movable element co-operating with the die, yielding blank holding means, spring cushioning means providing the said blank holding means with a substantially unvarying pressure during the operative stroke of the 45 said movable element, the last recited means including a plurality of resilient elements and means individual to the said movable element and the said blank holding means for respectively controlling the operation of 50 the said resilient elements, and fluid pressure means operating automatically to restrain "back lash" caused by the release of the pressure upon the blank holding means as the said movable elements recedes.

15. A draw press including a forming die, 55 a movable element co-operating with the die, yielding blank holding means, spring cushioning means providing the said blank holding means with a substantially unvarying pressure during the operative stroke of the 60 said movable element, the last recited means including a plurality of resilient elements and means individual to the said movable element and the said blank holding means for respectively controlling the operation of 65 the said resilient elements, fluid pressure means for restraining "back lash" caused by the release of the pressure upon

the blank holding means as the said movable element recedes, and means for varying at will the degree of the fluid pressure.

16. A draw press including a forming die, 70 a movable element co-operating with the die, yielding blank holding means, spring cushioning means providing the said blank holding means with a substantially unvarying pressure during the operative stroke of the 75 said movable element, the last recited means including a plurality of resilient elements and means individual to the said movable element and the said blank holding means for respectively influencing the said resilient elements, and means for varying at will the 80 stress of the said resilient elements, one with relation to the other.

17. A draw press including a forming die, 85 a movable element co-operating with the die, yielding blank holding means, spring cushioning means providing the said blank holding means with a substantially unvarying pressure during the operative stroke of the 90 said movable element, the last recited means including a plurality of resilient elements and means individual to the said movable element and the said blank holding means for respectively influencing the said resilient elements, and means individual to the 95 said resilient elements for independently varying the stress of the said resilient element and one with respect to the other.

18. A draw press including a forming die, 100 a movable element co-operating with the die, yielding blank holding means and spring cushioning means providing the said blank holding means with a substantially unvarying pressure during the operative stroke of the 105 said movable element, the last recited means including a plurality of resilient elements and means individual to the said movable element and the said blank holding means for respectively controlling the operation of the said resilient elements, and means for restraining "back lash" caused by 110 the release of the pressure upon the blank holding means as the said movable element recedes, the said restraining means including a relatively movable cylinder and piston one being anchored to a fixed part of the 115 press and the other being operatively connected with a movable part of the press, and means for introducing a fluid into the cylinder.

19. A draw press including a forming die, 120 a ram co-operating with the forming die, a blank holding member co-operating with the die, a plurality of separate cushioning means co-operating with the said blank holding member for yieldingly restraining the member in its operation with respect to the said ram, the said cushioning means providing the blank holding means with a substantially unvarying pressure during the 125 active stroke of the said movable element, 130

and means individual to the said cushioning means whereby the pressure upon the said blank holding member may be varied at predetermined points throughout the area 5 of the said blank holding member.

20. A draw press including a forming die, a ram co-operating with the forming die, a blank holding member co-operating with the die, a plurality of separate cushioning means co-operating with the said blank holding member for yieldingly restraining the member in its operation with respect to the said ram, the said cushioning means providing the blank holding means with a substantially unvarying pressure during the active stroke of the said movable element, means individual to the said cushioning means whereby the pressure upon the said blank holding member may be varied at predetermined points throughout the area of the said blank holding member, and fluid pressure means for restraining "back lash" caused by the release of the pressure of the said movable element upon the said blank holding member when the said movable element recedes.

21. A draw press including a forming die, a ram co-operating with the forming die, a blank holding member co-operating with the die, a plurality of separate cushioning means co-operating with the said blank holding member for yieldingly restraining the member in its operation with respect to the said ram, the said cushioning means providing the blank holding means with a substantially unvarying pressure during the active stroke of the said movable element, means individual to the said cushioning means whereby the pressure upon the said blank holding member may be varied at predetermined points throughout the area of the said blank holding member, and fluid pressure means for restraining "back lash" caused by the release of the pressure of the said movable element upon the said blank holding member when the said movable element recedes.

22. A draw press including a forming die,

a ram co-operating with the forming die, a blank holding member co-operating with the die, a plurality of separate cushioning means co-operating with the said blank holding member for yieldingly restraining the member in its operation with respect to the said ram, the said cushioning means providing the blank holding means with a substantially unvarying pressure during the active stroke of the said movable element, means individual to the said cushioning means whereby the pressure upon the said blank holding member may be varied at predetermined points throughout the area of the said blank holding member, and fluid pressure means for restraining "back lash" caused by the release of the pressure of the said movable element upon the said blank holding member when the said movable element recedes, the said fluid pressure means including a relatively movable cylinder and piston one operatively connected with the blank holding member and the other anchored to a stationary part of the press and means for supplying fluid to the cylinder.

23. A draw press including a forming die, a movable member co-operating with the die, a blank holding member, a plurality of separate resiliently yielding elements resisting the movement of the blank holding member, each of the elements embodying spaced plates and a coiled spring therebetween, pins engaging the blank holding member and one of the said plates of one of said elements, pins engaging and operating one of the plates of the other of said elements and a movable part of the press whereby the pressure of the last recited element upon the said blank holding member will be relieved, and fluid pressure means for retarding the return movement of the blank holding means when the said movable member recedes.

In testimony whereof we have signed our names to this specification, on this 28th day of July, A. D. 1924.

R. W. GLASNER.
JOHN NELSON.
